UNITED STATES PATENT OFFICE

WALTER C. ULINE, OF NAPPANEE, INDIANA

FOLDABLE SETTEE

Application filed January 22, 1930. Serial No. 422,624.

The invention relates to folding settees, and has for its object to provide a device of this character which is light in weight, cheap to manufacture, of strong construction, and foldable within a small compass for storing, shipping and the like, the device being particularly adapted for use as a piece of porch or lawn furniture.

A further object is to provide a device 10 of this character in which front and rear units of pivoted legs interconnected in "lazy tongs" manner support the settee, said leg units being reinforced by an adjustable strut member.

15 A further object is to provide a device of this character in which seat rails carried by leg units hold canvas or other strong foldable material to form a seat, and back supporting members pivotally connected to the 20 seat rails hold foldable back forming material, the leg units, seat and back being arranged whereby they may fold together in a compact manner.

A further object is to provide a device of 25 this character having a vertical adjustable strut reinforcing the leg units intermediate their ends, said strut being adapted to support the leg units when the device is in operative position and to be extended to accommodate the folding of the leg units.

A further object is to provide a device of this character with means whereby the material forming the seat may be clamped to the seat rails and securely held in operative relation thereto throughout its width.

A further object is to provide a device of this character having front and rear units of leg members pivotally interconnected in lazy tongs manner by which seat rails are carried, 40 said seat rails mounting the seat and having pivotally connected thereto suitable back supporting members and arm rests; said leg units and seat being foldable longitudinally, the outer back supporting members and 45 arm rests being foldable against the outer ends of the device, and the center back supporting member being foldable upon the central seat rail.

With the above and other objects in view, 50 the invention resides in the combination and

arrangement of parts as hereinafter set forth, shown in the drawings described and claimed, it being understood that changes in the precise embodiment of the invention may be made within the scope of what is claimed 55 without departing from the spirit of the invention.

In the drawings:

Figure 1 is a perspective view of the settee in operative position. 60

Figure 2 is a perspective view of the settee in partially folded position.

Figure 3 is a perspective view of the settee in completely folded position.

Figure 4 is a view in side elevation of the 65 vertical supporting strut showing the extended position thereof in dotted lines.

Figure 5 is a view in front elevation of the vertical supporting strut showing the extended position thereof in dotted lines. 70

Figure 6 is an end view of one of the seat rails showing the manner in which the settee arm and back supporting member are carried thereby, the folded position of these members being shown in dotted lines. 75

Figure 7 is a perspective view of one of the seat rails illustrating the manner in which the canvas is clamped thereto.

Fig. 8 is a perspective view of the end of the intermediate seat rail showing the connection of the lazy tongs thereto. 80

Referring to the drawings, the numerals 10 and 11 designate front and rear leg units, respectively, which carry end seat rails 12 and center seat rail 13 between which extends 85 a sheet of canvas or other suitable material 14 to form a seat; and pivotally connected to the seat rails 12 and 13 are back supporting members 15 between which extends a sheet of canvas to form the back of the settee. 90

Each of the leg units 10 and 11 preferably comprises four legs 17 which are arranged in pairs, the legs of each pair being pivotally connected at their centers, as at 18, said pairs of legs being pivotally connected together at their ends, as at 19, to form units; the legs of each leg unit thus being interconnected in "lazy tongs" manner. The lower ends of the legs of each unit carry spacer members 20, and at their upper ends the legs 100

17 carry the outer and central seat rails 12 and 13, respectively, the legs whose upper ends carry the central seat rail 13 having a pivotal connection therewith by means of brackets 21 carried by the central seat rail.

5 Extending between the central spacer 20 and the under side of the central seat rails 13 intermediate the leg units is a strut member 22 adapted to support the center of the settee

10 and to reinforce the leg units. The strut member 22 is comprised of two vertically disposed bars, one bar 23 being carried by a bracket 24 carried by the central spacer member 20, and the other bar 25 being carried in

15 face contact with bar 23 by a bracket 26 carried by the central seat rail 13. Guide members 27 and 28 are carried by the bars 23 and 25, respectively, and act to hold the bars 23 and 25 together in parallel face contact but

20 permit them to move longitudinally with relation to each other. Pivotedly carried by the seat rail 13 adjacent the strut 22 is a U-

25 shaped locking member 29 which is adapted to fit into locking notches 30 formed in one side of the bars 23 and 25 to lock said bars

against movement relative to each other, said notches 30 registering when the leg units are in operative position. An arm 31 having one

30 end thereof pivotally carried by the locking member 29 forms means whereby a pivotal movement of the locking member 29 may be effected, the outer end of said arm being carried by the seat rail 13 by means of a stud 32

35 projecting from the seat rail and through a slot 33 formed in the arm 31 adjacent the end thereof. An arm 34 formed at the outer end of arm 31 facilitates gripping thereof, and a

35 spring 35 carried by the seat rail 13 engages the arm 31 to normally hold said arm in re-

40 tracted locked position. Upon release of the locking member 29 from the locking notches in the bars 23 and 25 the strut is permitted to be extended, as shown in dotted lines in Figures 4 and 5, to accommodate the lengthening

45 of the distance between the spacer 20 and the seat rail 13 caused by folding of the leg units.

Bars 36 are pivotally connected with the end seat rails 12 by means of hinges 37, and the end back supporting members 15 are

50 mounted on said bars, said end back supporting members being adapted to swing outwardly through an arc of 180 degrees with relation to the settee so that said members may

55 lay alongside said leg units when folded instead of projecting outwardly therefrom.

The arm supporting posts 38 are also mounted on the bars 36, and the arms 39 are carried by the posts 38 and the back supporting members 15, said arms thus being adapted to

60 pivot with the back supporting members. A bar 40 is carried by the central seat rail 13, and to the rear end of this bar is hinged the central back supporting member 15 by means

65 of the hinge 41, whereby this central back supporting member may fold forwardly into

superposed relation with the bar 40, as shown in Figure 2. Each of the back supporting members 15 has an enlarged portion 42 formed substantially centrally therein to provide a shoulder to position the lower end of the back forming piece of canvas 16, and has an enlarged knob 43 formed at the upper end thereof to prevent the canvas from slipping off of said members. The ends and center of the canvas back 16 are provided with loops 44 which are easily fitted over and around the back supporting members and which rest upon the shoulders formed by the upper ends of portions 42 thereof.

70 Each of the seat rails 12 and 13 is provided with a longitudinally extending groove 45

80 on its upper face into which a metal bar 46 of slightly smaller width and thickness is adapted to be disposed and held by means of

85 screws 47, the bars 46 carried by the outer seat rails 12 forming means to clamp the ends of the canvas sheet 14 forming the seat to the

seat rails in said grooves 45, and the bar carried by the central seat rail 13 positioning

90 the center of the seat forming canvas so that it will not be unduly stretched when only one side of the settee is used. These metal clamping bars 46 hold the canvas firmly in place throughout its width, and form

95 means whereby the canvas seat may be easily adjusted to take up the stretch thereof by

loosening the bars and stretching the canvas, said canvas or other fabric forming the seat being required to be taut when the settee is

100 arranged in operative position. In the under sides of the seat rails 12 are formed V-

105 shaped longitudinal grooves 48 which are so positioned with respect to the pivot point

49 of the hinge 37 that the grooves will receive an edge of the bars 36, as shown in

110 Figure 6, when the settee is folded up, thus permitting the leg carried by the seat rail and the back supporting member to be folded in substantially parallel relation.

The settee is shown in operative position in Figure 1; and in Figure 2 it is shown in partially folded position, the locking mem-

115 ber 29 having been released from the locking notches in the strut bars to permit the strut 22 to be extended and the leg units to be folded together. The partial folding of the legs as shown in Figure 2 is sufficient to slacken

120 the seat member 14 and the back member 16 whereby the loops 44 of the back may be re-

125 moved from the end back supporting mem-

bers and the back may be laid upon the seat member 14 by forward pivotal movement of

130 the central back supporting member. Upon the removal of the back therefrom, the end

135 back supporting members may be swung out-

wardly for 180 degrees and the legs completely folded so that the settee assumes the

140 position shown in Figure 3 in which it oc-

The invention having been set forth, what is claimed as new and useful is:

1. In a settee, front and rear units of leg members pivotally interconnected in lazy tongs manner, spacers extending between the lower ends of said leg units, seat rails carried by the upper ends of said leg units, and a strut extending between the center seat rail and the center spacer to support said leg units in operative position. 5
2. In a settee, front and rear units of leg members pivotally interconnected in lazy tongs manner, spacers connecting the lower ends of said leg units, seat rails carried by said leg units, and a strut carried by said leg units, said strut comprising a vertical bar carried by one of said spacers, a bar carried by one of said seat rails and contacting said first named bar, and means adapted to lock said bars in operative supporting position. 15
3. In a settee, front and rear units of leg members pivotally interconnected in lazy tongs manner, spacers connecting the lower ends of said leg units, seat rails carried by said leg units, and a strut supporting said leg units in operative position, said strut comprising a vertical bar carried by one of said spacers, a bar carried by one of said seat rails in face contact with said first named bar, 25 guide members for guiding the movement of said bars one relative to the other, and means for locking said bars in operative position. 30
4. In a settee, front and rear units of leg members pivotally interconnected in lazy tongs manner, spacers connecting the lower ends of said leg units, seat rails carried by said leg units, and a strut supporting said leg units in operative position, said strut comprising a vertical bar carried by one of 35 said spacers, a bar carried by one of said seat rails in face contact with said first named bar, guide members holding said bars in face contact and guiding the movement thereof one relative to the other, and spring pressed 40 means for locking said bars in operative position. 45
5. In a settee, front and rear units of leg members pivotally interconnected in lazy tongs manner, spacers connecting the lower ends of said leg units, seat rails carried by said leg units, and a strut supporting said leg units in operative position, said strut comprising a vertical bar carried by one of said spacers, a bar carried by one of said seat rails 50 in face contact with said first named bar, guide members guiding the movement of said bars one relative to the other, said bars having locking notches formed therein, and means adapted to engage said notches to lock 55 said bars in operative position. 60
6. In a settee, front and rear units of leg members pivotally interconnected in lazy tongs manner, spacers connecting the lower ends of said leg units, seat rails carried by said leg units, and a strut supporting said 65
- leg units in operative position, said strut comprising a vertical bar carried by one of said spacers, a bar carried by one of said seat rails in face contact with the first named bar, guide members guiding the movement of said bars one relative to the other, said bars having locking notches formed therein, a locking member engageable in said notches to lock said bars in operative position, and a spring controlling said locking member to hold it in locking position. 70
7. In a settee, front and rear units of leg members pivotally interconnected in lazy tongs manner, spacers connecting the lower ends of said leg units, seat rails carried by said leg units, and a strut supporting said leg units in operative position, said strut comprising a vertical bar carried by one of said spacers, a bar carried by one of said seat rails in face contact with said first named bar, 80 said bars having locking notches formed therein, guide members guiding the movement of the bars one relative to the other, a locking member pivotally carried by said seat rail and engageable in said notches to lock said bars in operative position, and a spring adapted to hold said locking member in locking position. 85
8. In a settee, front and rear units of leg members pivotally interconnected in lazy tongs manner, spacers connecting the lower ends of the leg units, seat rails carried by said legs units, and a strut supporting said leg units in operative position, said strut comprising a vertical bar carried by one of said spacers, a bar carried by one of said seat rails in face contact with said first named bar, said bars having locking notches formed therein, guide members guiding the movement of the bars one relative to the other, a locking member engageable in said locking notches, an operating arm carried by said locking members, and a spring engaging said operating arm to hold said locking member in operative position. 95
9. In a settee, front and rear units of foldable legs, seat rails carried by said legs, bars carried by said outer seat rails and adapted to swing in an arc partially about said rails and in parallel relation thereto, back supporting members carried by said bars, said outer seat rails having longitudinal grooves formed in the bottom sides thereof adapted to receive an edge of the bar when folded to permit the leg carrying the seat rail and the back supporting member carried by said bar to assume substantially parallel positions when the settee is folded. 115
10. In a settee, front and rear units of pivotally connected legs, seat rails carried by said legs units, bars pivotally carried by said rails and adapted to swing in an arc partially thereabout, back supporting members carried by said bars, said rails each having a V-shaped groove formed in the bottom 120
- 115

thereof adapted to receive a corner portion of said bar whereby said back supporting members may be positioned substantially parallel said legs.

11. In a settee, front and rear units of leg members pivotally interconnected in lazy tongs manner, spacers extending between the lower ends of said leg units, seat rails carried by the upper ends of said leg units, and a strut extending between the center seat rail and the center spacer to support said leg units in operative position said strut comprising a pair of members shiftable relative to each other to accommodate folding of said leg units, and means locking said strut against extension.

In testimony whereof I affix my signature.
WALTER C. ULINE.
